WALTER J. COOK, OF GENEVA, NEW YORK

PNEUMATIC DRAFT REGULATOR

Application filed July 2, 1928. Serial No. 290,013.

This invention relates to a new and improved pneumatic draft regulator for use with forced draft systems for boilers and furnaces.

5 In order that low grade or finely divided fuel may be used in heating boilers and furnaces it is necessary that some means be provided whereby air may be fed to the bed of fuel with greater rapidity and in greater volume than would be given by a natural draft. This result is usually accomplished by providing an electric motor from which is operated a fan or blower which sends air into the ash pit of the boiler or furnace underneath 10 the bed of fuel. Such electric motor may be started and stopped manually, if desired, but is usually controlled by thermostatic means.

When air under pressure is being sent into 20 the ash pit of a boiler or furnace no opening other than the opening through which the air enters can be present in the ash pit because if it were the air under pressure would expel ashes and embers from the ash pit into the furnace room. This being the case in 25 all of the forced draft systems known to the art it has been customary upon installation to hermetically seal the clean out door and draft door which is usually present in the ash 30 pit of the boiler or furnace. When this is done the only draft which can ever be furnished for the fire must come from the blower. Under these conditions there can be no draft for the fuel when the blower is not 35 operating. Such an arrangement is uneconomical because of the fact that it does not take advantage of the natural draft when the blower is not operating. In other words, the 40 bed of fuel is either subjected to a draft under pressure or it is deprived of any draft at all.

Furthermore in installations of this character there is a strong possibility that unburned gases will accumulate on the surface 45 of the fuel, which gases frequently are ignited when the blower is started and the bed of fuel again placed under forced draft. Such ignition of accumulated gases will cause an explosion which may and sometimes 50 does cause considerable damage.

The main object of my invention is to construct a means which may be used in conjunction with a forced draft system and be operated thereby, which means will insure that the ash pit will be closed while the 55 blower is in operation but which will cause the opening of a door into the ash pit when the blower ceases operation so that the bed of fuel may then receive the natural draft which the boiler or furnace itself provides. 60

Another object is to provide a means whereby the evacuation of unburned gases from the fire pot of the boiler or furnace will be accelerated.

Another object is to provide a means for 65 utilizing a portion of the air from the blower to assist in the combustion of the fuel.

Other objects and advantages relate to the size, shape and arrangement of parts all as will more fully appear from the following 70 description taken in conjunction with the accompanying drawings in which:—

Figure 1 is an elevation, partially broken away, of a boiler and blower with my apparatus installed.

Figure 2 is a section on line 2—2 of Figure 1.

Figure 3 is a longitudinal vertical section through my device.

Figure 4 is an elevation, partially broken away, and partially in section of my device.

Figure 5 is a section on line 5—5 of Figure 3.

Figure 6 is a vertical view, partially in section, of my air jet.

My device may be used in conjunction with any boiler or furnace with which the forced draft system is used but for the purpose of explaining the functioning of my device I have here shown a boiler —1— of the type usually called a round boiler having the usual ash pit —2—, fire pot —3— and header —4—. It is also provided with the usual clean-out door —5—, draft door —6—, clinker door —7— and fuel door —8—.

A blower —9— operated from any convenient source of power, none being here shown, is located adjacent the ash pit —2— with a discharge opening —10— in communication with the ash pit —2—. The grates, 100

not shown, on which the fuel —11— is supported are positioned on the top of the ash pit so that the air from the blower —9— will strike the bottom of the bed of fuel —11—. The products of combustion are removed from the boiler through the ordinary smoke stack —12—.

A regulator bar —13— is pivotally mounted above the boiler and has depending from one end a chain —14— connected to the draft door —6— so that the pivoting of the regulator bar —13— about its pivot will open or close the draft door —6—. On the opposite end of regulator bar —13— is provided a weight —15— normally holding that end of regulator bar beneath the pivot which will cause the chain —14— to be moved upwardly to hold the draft door —6— in the open position. I also provide a diaphragm —16— in operative contact with the end of the regulator bar —13— from which chain —14— depends. Diaphragm —16— is connected to the steam chamber, not shown, in header —4— so that when a certain amount of steam is present the diaphragm —16— will be forced downwardly to overcome the action of weight —15— with the result that chain —14— will be lowered and draft door —6— closed.

My draft regulator —17— is positioned between ash pit —2— and blower —9— and consists of an inlet head —18— to which is connected the discharge opening —10— of the blower —9—. Inlet head —18— is preferably made of cast iron and carries at its forward end a gate —19— hook shaped in cross section and being pivotally mounted in the top edge of inlet head —18—. Inlet head —18— is provided on its inner end with opposed flanges —20—, one only being shown, of a size and shape conforming with the size and shape of gate —19— so that when gate —19— is in the down position its edges will contact with flanges —20— to close the opening through inlet head —18—. Gate —19— carries a shaft —21— which is journaled in inlet head —18— and extends outwardly therefrom, shaft —21— being the pivot from which gate —19— is suspended. I also provide on the bottom of inlet head —18— a baffle —22— extending outwardly and upwardly and so positioned that gate —19— when pivoted will be moved along the upper surface of baffle —22—.

A discharge head —23— preferably made of cast iron is connected to a discharge pipe —24— which in turn opens into ash pit —2—. Inlet head —18— and discharge head —23— are joined together by a casing —25— to provide an operating chamber for gate —19—.

On the top of inlet head —18— is provided an upwardly extending air tube —26— carrying a regulating damper —27—. Air tube —26— has an opening in its bottom end angularly disposed with relation to discharge

opening —10— of blower —9— so that when air is being discharged through discharge opening —10— a portion of such air will enter air tube —26— and proceed upwardly therethrough.

In the upper surface of discharge head —23— is a second air tube —28— which extends upwardly therefrom and which is provided with a damper —29—. Air tube —28— has a spoon shaped lower end which extends downwardly into the path of the air passing through discharge head —23— so that a portion of such air will enter air tube —28— and proceed upwardly therethrough.

The upper end of air tube —28— is connected to an air jet —30— which is positioned on the inside of smoke stack —12— with its discharge opening pointing upwardly.

Air tube —26— extends laterally into fire pot —3— and carries on its end a discharge nozzle —31— which is positioned above the fuel —11—. Discharge nozzle —31—, as perhaps may best be seen from Figure 2, is preferably formed with a curved forward end —32— in which are provided a plurality, in this case shown as seven, of apertures —33— in spaced relation so that the air passing through air tube —26— into discharge nozzle —31— will be distributed through apertures —33— to different parts of fire pot —3—. Air tube —26— is held in position in fire pot —3— by means of lock nuts —34— and —35—, air tube —26— being threaded for such purpose.

As perhaps may best be seen from Figures 4 and 5, shaft —21— carrying gate —19— carries a crank —36—. Crank —36—, as perhaps may best be seen from Figure 1, is connected by means of a chain —37— passing through a pulley —38— to the end of regulator bar —13— on which weight —15— is positioned so that the downward movement of crank —36— caused by the rotation of shaft —21— will cause the end of regulator bar —13— to which it is attached to be moved upwardly thereby causing chain —14— to move downwardly and permit draft door —6— to close. Crank —36—, as perhaps may best be seen from Figure 4, is so disposed with relation to gate —19— that the upward movement of gate —19— will cause the downward movement of crank —36— due to the rotation of shaft —21— and conversely the downward movement of gate —19— will cause the upward movement of crank —36—. In Figure 4 I show in heavy lines gate —19— closed with crank —36— in the up position and I show in dotted lines gate —19— in the raised position and crank —36— in the lowered position.

When the blower —9— is not operated the relation of parts is as shown in Figure 1 with draft door —6— open and with crank —36— in the raised position. When blower —9— is started in operation the air passing through

discharge opening —10— and inlet head —18— will strike gate —19— and force it upwardly and the continuing current of air will hold gate —19— in this raised position. 5 The operation of raising gate —19— is facilitated due to the spoon shape of gate —19— and also due to the fact that the baffle —22— is so disposed as to direct the air current against the face of gate —19—. When gate 10 —19— has thus been raised crank —36— will have been moved downwardly which will cause regulator bar —13— to be pivoted and draft door —6— closed.

When blower —9— is stopped and no air 15 is moving through discharge opening —10— and inlet head —18— gate —19— will drop to the closed position which will cause crank —36— to be raised, this in turn will loosen chain —37— and permit weight —15— to 20 move downwardly pivoting regulator bar —13— and raising chain —14— which will result in the opening of draft door —6— to permit the fuel —11— to receive the natural draft provided by the boiler —1—.

25 When blower —9— is in operation a certain amount of air will be forced through air tube —26— into and through discharge nozzle —31—. Discharge nozzle —31— being positioned above the fuel —11— will be heated so that the air which passes through it will also become heated before it is discharged into fire pot —3—. This supplemental supply of heated air through discharge nozzle —31— is a very material aid 30 to the combustion of the fuel —11—.

When blower —9— is operating a supply 40 of air will be forced through air tube —28— and out through air jet —30— into smoke stack —12—. This discharge of air upwardly in smoke stack —12— will materially increase the suction in smoke stack —12— and will accelerate the removal of the products of combustion from the fire pot —3— thereby preventing any accumulation of unburned 45 gases in smoke stack —12—.

The amount of air which it is desired to send through air tubes 26 and 28 can be regulated as desired by means of dampers —27— and —29—, respectively.

50 It will be understood that the size of the different parts of my apparatus may be varied as desired depending upon the type of boiler or furnace with which my device is to be used. It will also be understood that the opening 55 and closing of draft door —6— may be accomplished irrespective of any steam regulation by means of a diaphragm —16— as above described, the only requirement being a regulator bar such as —13—, a weight —15— and

60 chains —14— and —37—, for although I have shown and described a specific structure and form of part as an exemplification of an embodiment of my invention I do not desire to restrict myself to the exact shape, size or relation of parts as various changes may be

made within the scope of the appended claims.

I claim:

1. In a fuel burning apparatus, an ash pit, a bed of fuel above the ash pit, a fire pot above the bed of fuel, a draft door opening into the ash pit, means for opening such door, an exhaust flue leading from the fire pot, a source of air under pressure, means for introducing such air into the ash pit, means actuated by the air under pressure for closing the draft door, and means for introducing air under pressure into the fire pot. 70

2. In a fuel burning apparatus, an ash pit, a bed of fuel above the ash pit, a fire pot above the bed of fuel, a draft door opening into the ash pit, means for opening such door, an exhaust flue leading from the fire pot, a source of air under pressure, means for introducing such air into the ash pit, means actuated by the air under pressure for closing the draft door, means for introducing air under pressure into the fire pot, and additional means for introducing air under pressure into the exhaust flue. 80

3. In a fuel burning apparatus having a draft door, means for opening such draft door, a source of air under pressure, means for introducing air under pressure into the fuel burning apparatus, means actuated by the air under pressure for closing the draft door, such means including a gate pivotally mounted in the path of the air under pressure. 90

4. In a fuel burning apparatus having a draft door, means for opening such draft door, a source of air under pressure, means for introducing air under pressure into the fuel burning apparatus, means actuated by the air under pressure for closing the draft door, such means including a gate pivotally mounted in the path of the air under pressure, and a baffle for directing the air under pressure against the gate. 100

5. In a fuel burning apparatus, an ash pit, a bed of fuel above the ash pit, a fire pot above the bed of fuel, a draft door opening into the ash pit, means for opening such door, an exhaust flue leading from the fire pot, a source of air under pressure, means for introducing such air into the ash pit, means actuated by the air under pressure for closing the draft door, and means for introducing air under pressure into the fire pot, such last named means including a pipe having a portion thereof disposed in the path of the air under pressure. 110

6. In a fuel burning apparatus, an ash pit, a bed of fuel above the ash pit, a fire pot above the bed of fuel, a draft door opening into the ash pit, means for opening such door, an exhaust flue leading from the fire pot, a source of air under pressure, means for introducing such air into the ash pit, means actuated by the air under pressure for closing the draft door, means for introducing air 120

under pressure into the fire pot, and additional means for introducing air under pressure into the exhaust flue, such last named means including a pipe having a portion thereof disposed in the path of the air under pressure.

5 In witness whereof I have hereunto set my hand this 25th day of June, 1928.

WALTER J. COOK.
